UNITED STATES PATENT OFFICE.

GUSSIE G. GRIFFIN, OF MULBERRY, FLORIDA.

CURTAIN-POLE.

1,077,529.

Specification of Letters Patent.

Patented Nov. 4, 1913.

Application filed December 23, 1912. Serial No. 738,312.

To all whom it may concern:

Be it known that I, GUSSIE G. GRIFFIN, a citizen of the United States, residing at Mulberry, in the county of Polk, State of Florida, have invented certain new and useful Improvements in Curtain-Poles; and I do hereby declare the following to be a full, clear, and exact description of the invention, such as will enable others skilled in the art 10 to which it appertains to make and use the same.

This invention relates to curtain poles.

The object of the invention is the provision of a curtain pole which may be readily adjusted so as to be applicable to door 15 and window frames of different widths.

A further object of the invention resides in the provision of a curtain pole and fixture which is so constructed and arranged 20 that the connection of the curtain with the pole and the connection of the pole with the door or window frame will both be invisible when the pole is applied.

A still further object of the invention resides 25 in the provision of a curtain pole which will be simple in construction, ornamental, easily applied in proper relation to a door or window frame and which may be manufactured at a comparatively small 30 cost.

With the above and other objects in view the invention consists in the details of construction and in the arrangement and combination of parts to be hereinafter more 35 fully described and particularly pointed out in the appended claim.

In describing the invention in detail reference will be had to the accompanying drawings wherein like characters of reference 40 denote corresponding parts in the several views, and in which—

Figure 1 is a front elevation of the upper end of a door frame showing the improved pole applied. Fig. 2 a plan view of what 45 is shown in Fig. 1 with the pole in section. Fig. 3 a section on the line 3—3 of Fig. 1, and Fig. 4 a detail perspective view of a fragment of the tubular body portion of the pole.

50 Referring to the drawings, A indicates the door frame, B the improved curtain pole and C the curtain supported by the latter.

The curtain pole B is shown as comprising 55 a tubular body portion 10 having

a longitudinal slot 11 therein extending throughout the entire length of said body portion. Telescopically engaged over each end of the body portion 10 is a cap 11 provided at its 60 inner end with a recess 12 adapted to be brought into alinement with the slot 11 when said caps are applied. Extending from the closed end of one of the caps 11 inwardly of the latter is a tubular rod 13, 65 while a corresponding tubular rod 14 extends inwardly from the closed end of the other cap 11 and telescopically engages within the rod 13. Projecting outwardly from the closed end of each cap 11 is a 70 threaded stud 15 upon which is engaged an ornamental knob 16.

In connecting the curtain C to the pole the upper end of said curtain is provided with a hem through which is inserted the tubular 75 rod 13 while the cap 11 carrying said rod is detached from the body portion 10. The cap 11 carrying the rod 13 is then engaged over one end of the body portion 10, the curtain C being guided through the slot 11. 80 The heads of nails 17 suitably secured to the frame A are then passed through the open end of the body portion 10, the shanks of said nails passing into the slot 11. After the body portion 10 has been brought into 85 proper relation to the frame A the rod 14 is telescopically engaged within the rod 13 and the cap carrying the rod 14 telescopically engaged over the other end of the body portion 10 when the application of the pole will 90 be complete.

In applying portières of considerable weight and thickness to the pole no hem need be provided in the upper end of the portière, it being only necessary to carry 95 same around the rod 13 and then work the double thickness resulting through the slot 11 which latter is sufficiently narrow to clamp the body and overlapped ends of the portière together.

100 What I claim is:

The combination with a supporting part, of headed members projecting therefrom, a curtain pole comprising a tubular body portion provided with a longitudinal slot extending throughout its length, said body portion detachably engaging over the heads of said members with the shanks of the latter disposed in said slots whereby the body portion is supported by the members, caps 110

telescopically engaged from each end of the body portion, and tubular rods carried by and extending inwardly from the heads of said caps and telescoping with each other 5 whereby a curtain may be engaged with the outer telescoping tubular rod and inserted within the bore of the body portion.

In testimony whereof, I affix my signature, in the presence of two witnesses.

GUSSIE G. GRIFFIN.
